UNITED STATES PATENT OFFICE

CHARLES H. AYARS, OF SALEM, NEW JERSEY, ASSIGNOR TO AYARS MACHINE COMPANY, OF SALEM, NEW JERSEY, A CORPORATION OF NEW JERSEY

CAN FILLING DEVICE

Application filed October 14, 1930. Serial No. 488,578.

This invention relates to can filling devices, and has for an object to provide structural features, forming a part of the entire organization of a canning machine, which provides 5 improved means for insuring the introduction into the can, of the entire volume of material measured for that purpose.

A further object of the invention is to provide a funnel-like device, directed toward a 10 supported can, with improved means for varying the delivering orifice in said funnel.

A further object of the invention is to provide about such funnel construction, a space to permit the escape of air as the can is filled, 15 to insure the proper filling of the can.

A further object of the invention is to provide in the structure, surrounding the funnel, and between which structures and the air space so provided, improved means to insure 20 the drip of any splashed material back into the can.

The invention comprises, in combination with a rotating structure, a rotating table for supporting a plurality of cans, a structure located above said rotating table, and provided 25 with a plurality of funnels of the proper number to co-act with the number of cans supported upon the table, and with an air space, or vent, surrounding each of the funnels, said vent being smaller than the size of 30 the can, and with a groove in the supporting structure surrounding such vent, which groove forms a sharp edge to insure rapidity of drip.

35 The invention is directed to other objects and possesses other features of novelty and advantage, some of which, together with the foregoing, will be hereinafter more fully set forth.

40 In the drawings:

Figure 1 is a top plan view of a fragment of a canning machine, showing the tops of adjacent funnels.

45 Figure 2 is a sectional view, taken on a circumference, indicated by line 2-2 of Figure 1.

Figure 3 is a horizontal sectional view, taken on line 3-3 of Figure 2, and

50 Figure 4 is an inverted plan view, taken on line 4-4 of Figure 2.

Like characters of reference indicate corresponding parts throughout the several views.

The improved can filling device, which forms the subject matter of this application, is adapted to be associated with rotating canning machines, of various types, and no showing of any machine part, is to be construed as a limitation upon the present invention. A rotating table 10, is provided for supporting a plurality of cans 11, beneath a rotating 55 turret 12, such turret rotating in synchronism with the table 10. Any approved means is provided for raising or lowering the table 10, or any part thereof, for properly clamping the cans under the turret 12.

60 The turret 12, is provided with a plurality of openings 13, formed therethrough, and so positioned, as to be concentric of the cans 11, as positioned upon the table 10. This opening may be of such size as may be found 65 convenient, the size of the can being taken into consideration. It should, however, provide some overlap, as indicated at 14, and a groove 15, is formed in said overlap providing a sharp rib 16, located above the can.

65 Within the openings 13, funnels 17 are positioned, and mounted in concentric positions, in said openings, in any approved manner, as by ears 18, formed thereon and bolted to the turret 12. In any case, the size of the 70 funnel, where it passes through the openings 13, is less than the size of said opening so that an annular vent space is provided entirely around said funnel. The funnel is preferably provided with a sharp lower edge 75 19, and a bushing 20, is inserted into the lower end of said funnel, such bushing being merely dropped in and held by gravity, and replaced by other bushings, constricting the delivery

80 orifice of the funnel. Such bushings will be 85 changed from time to time, as the material being operated upon is changed, that is to say, the more fluid the material, the smaller the orifice, and conversely, the greater the viscosity, the larger the orifice. The structure, 90 above outlined, has been provided in view of the difficulty in filling cans without proper vents.

95 To prevent spilling or slopping the contents, it is necessary to clamp the can against 100

the under side of the turret, and thereby, make the joint approximately air-tight so that the material being delivered to the can, from the funnel, forms a seal which prevents the proper flow of the material. By venting, the air seal is broken, and the material flows uninterruptedly through the orifice, out of the funnel, or the bushing, into the can. By providing the groove 15, with the sharp rib 16, any of the contents slopped upwardly, because of the discharge into the can, will drip from the sharp edge, into the can with minimum adherence.

Of course, the can filling device, herein illustrated, may be modified in various ways without departing from the invention herein set forth and hereinafter claimed.

The invention is hereby claimed as follows:

1. A can filling device comprising a can supporting structure, a super-structure arranged to clamp cans upon the supporting structure and provided with openings communicating with the several cans, drip speeding parts carried by said super-structure overlying the can, funnels inserted through said openings and forming a vent between the funnel and the walls of the openings, and orifice constricting members positioned in the smaller ends of the funnels.

2. A can filling device comprising a can supporting structure, an annulus arranged to engage the top edge of and clamp a can upon the supporting structure, an inlet conduit introduced through the annulus and spaced annularly therefrom to form a vent, and a downwardly directed sharp drip rib upon the annulus.

3. A can filling device comprising a can supporting structure, an annulus arranged to engage the top edge of and clamp a can upon the supporting structure, an inlet conduit introduced through the annulus and spaced annularly therefrom to form a vent, and a downwardly directed sharp drip rib upon the inner edge of the annulus.

4. A can filling device comprising a can supporting structure, an annulus arranged to engage the top edge of and clamp a can upon the supporting structure, an inlet conduit introduced through the annulus and spaced annularly therefrom to form a vent, and a downwardly directed sharp drip rib upon the annulus and defined by an annular groove in the underside of the annulus.

5. A can filling device comprising a can supporting structure, an annulus arranged to engage the top edge of and clamp a can upon the supporting structure, an inlet conduit introduced through the annulus and spaced annularly therefrom to form a vent, and a downwardly directed sharp drip rib upon the inner edge of the annulus and defined by an annular groove in the underside of the annulus.

6. A can filling device comprising a can supporting structure, an annulus arranged to engage the top edge of and clamp a can upon the supporting structure, an inlet conduit introduced through the annulus and spaced annularly therefrom to form a vent and provided with a lower edge tapered to sharpness, and a downwardly directed sharp drip rib upon the annulus.

7. A can filling device comprising a can supporting structure, an annulus arranged to engage the top edge of and clamp a can upon the supporting structure, an inlet conduit introduced through the annulus and spaced annularly therefrom to form a vent and provided with a lower edge tapered to sharpness, and a downwardly directed sharp drip rib upon the annulus and defined by an annular groove in the underside of the annulus.

8. A can filling device comprising a can supporting structure, an annulus arranged to engage the top edge of and clamp a can upon the supporting structure, an inlet conduit introduced through the annulus and spaced annularly therefrom to form a vent and provided with a lower edge tapered to sharpness, and a downwardly directed sharp drip rib upon the inner edge of the annulus and defined by an annular groove in the underside of the annulus.

In testimony whereof I have signed my name to this specification.

CHARLES H. AYARS.
